Primary Examiner — Kendra Leslie Hamilton

(57) **CLAIM**

The ornamental design for a dog muzzle, as shown and described.

DESCRIPTION

FIG. 1 is a front perspective view of a dog muzzle, showing my new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a front, left perspective view of the dog muzzle of FIG. 1, shown in a condition use for clarity of disclosure.
FIG. 10 is an enlarged detail view of area 10 in FIG. 1 thereof;
FIG. 11 is an enlarged detail view of area 11 in FIG. 5 thereof; and,
FIG. 12 is an enlarged detail view of area 12 in FIG. 6. The broken lines in the drawings illustrate the portions of the dog muzzle, which form no part of the claimed design. The broken line showing of a dog in FIG. 9 depicts environmental subject matter and forms no part of the claimed design.

1 Claim, 12 Drawing Sheets
